WARDROBE FOR HALLS

Filed Feb. 10, 1927

Inventor:
by Karl Wilhelm Bülick
J. G. Knobels
Attorney.

UNITED STATES PATENT OFFICE

KARL WILHELM BÜLCK, OF NEUMUNSTER, GERMANY

WARDROBE FOR HALLS

Application filed February 10, 1927, Serial No. 167,252, and in Germany February 13, 1926.

This invention relates to a wardrobe for the hall which may be extended for hanging up a greater number of garments than normally. In the top part of the wardrobe an extensible or oscillatable bar is arranged at each side, on which cloth pegs are fixed, and behind the back wall of the wardrobe two auxiliary back walls are arranged adapted to be pulled out together with the extensible or oscillatable bars in order to enlarge the back wall of the wardrobe. The wardrobe has further on the front a cupboard for boots so that the looking glass in this front portion of the wardrobe cannot be covered with garments hanging on the wardrobe.

An embodiment of the invention is shown, by way of example, in the accompanying drawings in which:

Fig. 1 shows in perspective view a wardrobe for the hall with pulled out extension bars, and auxiliary back wall pulled out the latter being indicated by dash-dot lines.

Fig. 2 is a cross section on line 2-2 of Fig. 1.

Fig. 3 is a cross section on line 3-3 of Fig. 1.

On the back of the upper portion of a wardrobe for the hall two guide bars *a* and *b* are fixed which have at the outer end of their inner surfaces each one dove-tailed groove. In these dove-tailed grooves two bars *c* and *d* are shiftably mounted, so that the one bar *c* may be pulled out to the left and the other bar *d* to the right. Each bar *c* and *d* carries a number of cloth-hooks *e* which, when the bars are pushed in are accommodated between the back wall of the wardrobe and the guide bars *c* and *d*, as shown in Fig. 2. The hooks *e* may be hingedly fixed and spring controlled so that as soon as the corresponding bar is pulled out they are pressed by the action of the springs into the position of use, so that the interval between the back wall *f* of the wardrobe and the extensible bars may be as small as possible. Each bar *c* and *d* carries at the outer end a piece *g* or *h* standing at right angles to the bar and designed to cover the outer ends of the guide bars when the extensible bars are pushed in. Behind the back wall of the wardrobe auxiliary walls may

be shiftably arranged so that they can be pulled out together with the corresponding extensible bar in order to prevent the garments hung up on the extended bars from coming into contact with the wall, said extensible walls being rigid with the extensible bars. Fig. 1 shows at the left side an extensible wall *i* and at the right side an extensible wall *i'* in the pulled out position. The shiftable walls *i* and *i'* may be suspended on the extensible bars *c* and *d* as shown in Fig. 2.

Each extensible bar *c* and *d* has at its end a vertical arm *k* or *m* respectively in which two rods *n* and *o* are fixed which are designed to form a hat rack. In the central part of the wardrobe two tubes *r* and *s* are fixed between forwardly projecting brackets *p* and *q* so that the inner ends of the rods *n* and *o* penetrate into these tubes when the extensible bars are being pushed in. The hat-racks on the extensible bars are therefore also extensible.

A cupboard *t* for boots is arranged on the central portion of the wardrobe and closed by a roll cover which has ventilation holes. Owing to the roll cover instead of doors no space is occupied in front of the wardrobe for opening the cupboard. The cupboard for boots prevents that garments hung on the wardrobe can hide the looking glass *v* as the garments will be held away from the looking glass by the projecting cupboard *t*.

I claim:

In a wardrobe for halls with extensible side parts the combination of extensible bars with portions of an auxiliary wall suspended on them, lateral arms on said extensible bars, extensible rods carried by said lateral arms, and cloth-hooks on said extensible bars, said bars guided in a dove-tailed guide of the back wall, and an interval between said extensible bars and the back wall of the wardrobe for accommodating the cloth-hooks on said extensible bars when these bars are pushed in.

In testimony whereof I affix my signature.

KARL WILHELM BÜLCK.
